CLAIM

The ornamental design for a gaming machine as shown and described.

DESCRIPTION

FIG. 1 is a front perspective view of a gaming machine showing my new design;

FIG. 2 is a front view thereof;

FIG. 3 is a left side view thereof; and,

FIG. 4 is a right side view thereof.

The broken line showing is included for the purpose of illustrating portions of the gaming machine that form no part of the claimed design.

1 Claim, 4 Drawing Sheets(56)
